CYRUS W. BALDWIN, OF BOSTON, ASSIGNOR TO LAFAYETTE HUNTOON,
OF MILFORD, MASSACHUSETTS.

Letters Patent No. 76,140, dated March 31, 1868.

IMPROVEMENT IN STEAM-ENGINES.

The Schedule referred to in these Letters Patent and making part of the same.

TO ALL TO WHOM THESE PRESENTS SHALL COME:

Be it known that I, CYRUS W. BALDWIN, of Boston, county of Suffolk, and State of Massachusetts, have invented a new and useful Improvement in Steam-Engines; and do hereby declare the following to be a full, clear, and exact description thereof, due reference being had to the drawings, which accompany and make part of this specification, and in which—

Figure 1 is a plan,

Figure 2 an end elevation,

Figure 3 a vertical and transverse section of my invention.

Figures 4 and 5 are sections of the valve-ports, and

Figure 6 a vertical section of the two cam-shafts, to be hereinafter described, while

Figures 7, 8, and 9 are views showing the construction of the valves.

This invention has reference to or is an improvement upon that class of steam-engines in which two cylinders of different capacities are employed, the steam from the smaller cylinder being exhausted into and used expansively in the larger.

The object of this invention is to obtain in such class of engines the advantage of the well-known puppet-valves, and consists in the arrangement with such engines of a series of such valves, in manner and to produce results substantially as hereinafter explained.

One advantage, among others, of the above-described arrangement of the valves is, that by being placed at the bottom of or below the bottom of the cylinder or cylinders, the condensed water is allowed to escape freely and automatically from such cylinder. The mechanical construction and application, also, of the valves is such that they may be easily got at for inspection or repair, and are applied, in the first instance, with economy and ease.

In the above-mentioned drawings, A denotes the small cylinder; B, the large cylinder. C is the bed, the valves being numbered 1, 2, 3, 4, 5, and 6 respectively. D is the governor-shaft, on which is a small cam, E, which operates the valves by means of tappets a^2 a^3 on the arms a a' , which carry the levers b b' , attached to the stems of the valves 1, 3, 4, and 6. On the governor-shaft there is also a large cam, E', which operates the levers c c' , attached to the stems of the valves 2 and 5. On the governor-shaft D is also an incline, F, which is attached to the spindle G by means of a pin passing through a slot in the governor-shaft, which permits the spindle G and the incline F to be raised or lowered as the balls shall be dropped or raised by centrifugal force, the balls being connected with the spindle G. The incline F, being lowered with the spindle G, strikes the bell-crank d , which operates the catches e^2 e^3 , to release the levers c^2 c^3 , and allow the valves 1 and 6 to drop, as regulated by the governor. The governor-shaft is driven by means of a longitudinal shaft, running under the bed C, and connected with the governor-shaft D and main shaft by the proper gears, in such a manner that the governor-shaft D shall turn at the same speed as the main shaft. The cup puppet-valves are of a new and peculiar construction, which will be readily understood by reference to the accompanying drawings, the operation of which will be hereinafter described. The valves and ports are placed as near as possible to the large cylinder B.

The operation of the above-described arrangements will be readily understood to be with precision, certainty, and ease. The governor is so adjusted that, when the engine is working under a full load, the steam will be allowed to follow piston, in small cylinder A, the full stroke. Steam is first admitted from boiler, through the valve 1, to small cylinder A, by means of the cam E, which also closes it at the end of the stroke, or as the governor may determine, when valve 2 is opened by the cam E' and levers c c' , which permits the exhaust from small cylinder A to pass into large cylinder B, where it is expanded in proportion to the difference in the capacity of the two cylinders. Valve 2 closes at the end of the stroke, when valve 1 is again opened by cam E, which admits steam at the boiler-pressure into cylinder A. At the same time valve 5 is opened by the cam E', allowing the exhaust from cylinder A to pass into cylinder B; and valve 3 is opened by cam E, which exhausts from large cylinder into the open air; the small cam, E, opening the valves 1 and 3, which admit steam from

the boiler into small cylinder A, and exhausts from large cylinder into the open air. At the same time cam E opens valve 5, and allows the exhaust from small cylinder to pass into large cylinder B and be expanded. At the end of the stroke, the valves 1, 3, and 5 close simultaneously, and valves 6 and 4 are opened by cam E, which admits steam from the boiler into small cylinder A, and exhausts from large cylinder B into the open air, and large cam E', at the same time opening valve 2, which exhausts from small cylinder A into large cylinder B, where it expands.

This operation of the valves 6, 4, and 2 is the same as that of valves 1, 3, and 5, except it is on the return stroke, and on the opposite side of the pistons. If a part or all of the load at any time be taken from the engine, the balls rising, the moment the engine increases its speed, force the spindle G, with the incline F, down upon the bell-crank d, which operates the catches c^2 c^3 , releasing the levers c^2 c^3 , and the valves 1 and 6, closing and cutting off the supply of steam from the boiler to small cylinder A, shorter or longer, according as more or less amount of load is removed from the engine. This cut-off has a range through the whole length of stroke, and, in case of necessity, will cut off the supply of steam from the boiler entirely. The instant closing of the valve is secured by use of the springs e e e e e e .

The construction of the valves, as shown in figs. 7, 8, and 9 of the drawings, is very simple, and their action is with certainty and ease. It requires but one seat, which prevents any leakage by unequal expansion. The opening being on the side of the frustum of a cone or pyramid, causes the principal pressure to be inward and downward only, in the amount proportioned to the incline of the seat, which is only sufficient to prevent the valve from sticking. Any wear in the valve or seat will only cause them to fit more closely, if possible. It cannot cause leakage. The moment the valve rises, steam rushes into the port, both under and through the top of the valve, thus allowing ample and unobstructed passage for the steam. The closing of the valves is certain, without the use of other guides than the usual stuffing-box around the stem, the valve and seat themselves forming a sure guide.

I claim the arrangement of puppet-valves, with reference to that class of steam-engines in which two cylinders of different capacities, and exhausting from one to the other, are employed, substantially as herein shown and described.

I claim the arrangement of the valves, their casings, and the steam-passages, in relation to each other, and operating essentially as before explained.

C. W. BALDWIN.
